PAPER-FEEDING DEVICE.

1,137,553.

Specification of Letters Patent.

Patented Apr. 27, 1915.

Application filed September 24, 1913. Serial No. 791,530.

To all whom it may concern:

Be it known that I, JAY L. THOMPSON, a citizen of the United States, and a resident of Greensburg, in the county of Kiowa and State of Kansas, have invented a new and useful Improvement in Paper-Feeding Devices, of which the following is a specification.

My invention is an improvement in paper feeding devices for printing presses, and has for its object to provide mechanism for connection with the printing press, and comprising forwarding and receiving magazines for the printed matter, together with mechanism for feeding the sheets from the forwarding magazine to the press, and from the press to the receiving magazine, the said mechanism being automatic and fluid controlled.

In the drawings: Figure 1 is a side view of a printing press, provided with the improved feeding device, Fig. 2 is a longitudinal vertical section of the magazine showing the parts in one position, Fig. 3 is a similar view showing the parts in another position, Fig. 4 is an enlarged detail of a portion of Fig. 2, showing the delivery of the printed sheets to the receiving magazine, Fig. 5 is a detail perspective view of a portion of the feeding mechanism, Fig. 6 is a similar view of the forwarding magazine, Fig. 7 is a bottom plan view of the suction finger, Fig. 8 is a section on the line 8—8 of Fig. 7, looking in the direction of the arrows, Fig. 9 is a section on the line 9—9 of Fig. 5, and Fig. 10 is a perspective view of the lifting plate.

The present embodiment of the invention is shown in connection with a printing press 1, having the usual type bed 2, and the platen 3, the said platen being supported by the arms 4, which are connected to the platen at one end, and are journaled on the frame of the press at the other end as indicated at

45 The platen 3 is swung into contact with the type on the bed by means of a lever 6, the said lever being journaled on a shaft 7 connected with the frame of the press.

Arms 8 extend rigidly from the lever, and the said arms are connected at 9 to a roller which engages beneath the platen. It will be evident that when the lever is swung

into the dotted line position of Fig. 1, the platen will be swung into contact with the type on the bed as shown in dotted lines in 55 the said figure, and the lever is provided with an arm 10, extending in the opposite direction to the arms 8, and having a longitudinally extending slot 11, at its outer end.

An air pump 12 is secured to a base 13, 60 adjacent to the press, and the rod or stem 14 connected with the plunger of the pump is also connected with the arm 10, by means of a pin or bolt 15, which engages the slot 11. The air pump is connected by means of 65 a pipe 16, to a reservoir 17 supported on the base, and the said reservoir is provided at the center of its top 18 with an inlet valve 19, the said valve being spring controlled. A valve 20 is provided for checking the return of the air from the pump to the reservoir, and the valve 19 is for permitting the air pressure in the reservoir to be adjusted. The valve 19 is so arranged 70 that when the vacuum exceeds the predetermined point, the valve will open.

The forwarding magazine 21 is supported by arms 22, extending rearwardly and upwardly from the press, and the receiving magazine 23 is supported below the forwarding magazine, on the same arms 22. The sheets 24 to be printed are supported in an auxiliary magazine or holder 25, arranged within the magazine 21, and the said auxiliary holder or magazine is open at its 85 top, and at the side adjacent to the press, the said side being cut away at its upper edge. A flange 26 is however left at the said side adjacent to the bottom to prevent the sheets from becoming displaced.

Slide members 27 are arranged at the front and the bottom of the holder 25, and at the rear the said holder is supported by a coil spring 28. The spring bears at one end against the under face of the said holder, 95 and at the other end against the outer end of a plate 29, which extends rearwardly from the center of an arm 30, the said arm extending transversely of the upper face of the bottom of the forwarding magazine. The 100 said arm is provided with a crank 31 at its outer end and outside of the magazine, and the crank is pivoted to one end of a link 32, whose other end is connected with the platen

at the connection of the arm 8. A pair of rack bars 33 is connected with the forwarding magazine, the said bars being arc-shaped as shown, and having their convex edges upwardly, and the teeth of the rack bars are on the said convex edges.

The rack bars extend forwardly toward the press, the free ends of the said bars being above the type bed, and each of the 10 said free ends is provided with a lateral stop 34. A pinion 36 is journaled on each of the side members of the platen 3, (Fig. 5), each of the said pinions being secured to a stub shaft 37, supported by the adjacent side 15 member of the platen, and each of the pinions meshes with the adjacent rack bar 33. It will be noticed from an inspection of Fig. 5 that each of the side members of the platen 3 is channeled on its inner face to form a 20 guideway or passage 39, and a slide member or bar 40 is arranged to slide in the said passages, the said bar or slide member being transverse to the platen. The slide member or bar 40 is provided with a feeding or suc- 25 tion member or finger 41, to be later described in detail, and rack bars 35 are rigidly secured to the ends of the said slide member 40. The rack bars extend in the opposite direction from the press, and the 30 teeth of the rack bars are on the under faces thereof.

A pinion 38 is secured to the inner end of each of the stub shafts 37, and each of the 35 said pinions mesh with the adjacent rack bar 33. The rack bars slide in the passages 39, and it will be evident that whenever the platen is swung from the position of Fig. 2 to the position of Fig. 3, or in the reverse direction, the pinions 36 will be rotated by 40 their engagement with the rack bars 33, and the said pinions will in turn rotate the pinions 38, which will move the rack bars 35 and the slide bar or member 40 with respect to the platen. The suction member or finger 45 41 is provided with a nipple 42 at its inner end, for engagement by one end of a flexible pipe 43, the other end of the said pipe 43 being connected with the inlet 44 of the reservoir 17, before mentioned. From the nipple 42 passages 45 and 45^a lead to the opposite ends of a transverse recess 46, the said recess being in the under face of the finger. The movement of the lever 6 will operate the pump 20 to partially exhaust 50 the air from the reservoir 17, and to create suction through the pipe 43 from the recess 46 to the reservoir. The suction is sufficient to cause the uppermost sheet 24 in the holder 25 to stick to the under plane face of the 55 finger, as will be hereafter described.

The receiving magazine 23 is as before stated, arranged below the forwarding magazine 21, and a guide plate 47 extends from the said magazine to the rear face of

the platen, when the platen is in position 65 to receive a sheet to be printed. The base or bed of the platen is supported between the side members 3, below the slide member 40, and the said bed or body is provided with a transverse slot or passage 48, so arranged 70 with respect to the platen that when the platen is in inoperative position, that is, in the position of Fig. 2, the upper face of the guide plate 47 will be flush with the under or lower wall of the slot or passage 48. A 75 guide lip or flange 49 is connected with that face of the platen adjacent to the press, just above the slot or passage 48, and the said lip or flange is slightly above the level of that face of the bed or body of the platen 80 which receives the sheet 24 to be printed. The finger is however, below the under face of the slide bar or member 40, and does not interfere with the passage of the said slide bar or member.

The operation of the feeding mechanism is as follows:—When the lever is moved into the dotted line position of Fig. 1, the platen is moved to bring the sheet 24 thereon into contact with the type on the type bed 2. At 90 the same time, the pump 20 is operated to exhaust a portion of the air from the reservoir 17. At the same time the plunger of pump 20 is moved downwardly. When the lever 6 returns to the full line position of Fig. 1, the plunger of the pump 20 is lifted, and exhausts a portion of the air from the reservoir 17, thus creating a partial vacuum in the flexible pipe 43, and air is drawn into the passage 46 of the feeding finger 41. As 100 the platen returns to the position of Figs. 1 and 2, the pinions 36 are rotated by their engagement with the rack bars 33, and the said pinions in turn rotate the pinions 38, which move the rack bars 35 outward, carrying 105 with them the slide bar 40 and the suction finger 41 into the position of Fig. 2. When the platen comes to rest, the slide bar is at the upper edge of the body of the platen, and the suction finger 41 extends 110 above the said body. The return of the platen to its normal position moves the link 32 from the dotted line to the full line position of Fig. 1, and the said link swings the crank 31 of the arm 30 to lift the free end of the plate 29 from the upper face of the bottom of the magazine 21, and the plate lifts the holder 25 into the position of Fig. 2, that is, with the upper face of the topmost sheet in 115 the holder flush with the upper face of the platen bed or body. With the holder in this position, the suction or feeding finger 41 rests upon the upper face of the topmost sheet, and since there is a partial vacuum in 120 the passages of the said finger and in the pipe 43 and the reservoir 17, the topmost sheet will cling to the finger, and as the platen is again moved toward the type bed, 125

the topmost sheet will be drawn down into position to be impressed by the type on the bed. The platen moves to contact the said topmost sheet with the type bed, and on the 5 return movement, the pinions 36 and 38 are rotated in a direction to move the rack bars 35 and the slide 40 upwardly. The upper edge of the topmost sheet during its upward movement contacts with the lip 49, and the 0 said sheet is deflected through the passage 48 and over the guide plate 47 into the receiving magazine 23.

The operation of the device is entirely automatic so far as concerns the feed and delivery of the sheets. The movement of the platen to bring a sheet into contact with the type on the type bed, and to return the platen to its inoperative or normal position, causes first a sheet to be fed into position to 5 be employed, and second, the delivery of the sheet from the platen bed to the receiving magazine. When the platen is in the position of Fig. 2, the holder 25 is held in the position shown in the said figure, and when 10 the platen is impressing the sheet, the said holder takes the position of Fig. 3, so that there is no possibility of the sheets becoming displaced. The lower end of the holder, that is the portion of the holder which moves 15 upon the receiving magazine proper, has a limited sliding movement to insure that the topmost sheet will always be pressed against the under face of the suction finger. The said finger limits the movement of the lower 20 end of the holder. The forwarding magazine in the present instance is merely separated guide plates, each of which is provided with an inwardly extending flange 50, upon which the holder 25 moves. The said 25 holder is in fact the forwarding magazine for the sheets. The holder 25 is yieldingly supported, and it will be evident that as the sheets are removed, the spring 28 will tend to expand, to always hold the topmost sheet 30 in position to be engaged by the finger 41.

I claim:—

1. In combination with a printing press having a type bed and a platen mounted to swing toward and from the type bed, and 50 means for moving the platen, of a forwarding magazine for the printed sheets at the upper end of the platen when the platen is in inoperative position, a guide for the magazine, the magazine being slidable toward and 55 from the platen, means operated by the return of the platen to inoperative position for lifting the magazine into approximate parallelism with the platen, and feeding mechanism for engaging the topmost sheet and moving 60 it on to the platen operated by the movement of the platen.

2. In combination with a printing press having a type bed and a platen mounted to swing toward and from the type bed, and

the means for moving the platen, of a forwarding magazine for the printed sheets at the upper end of the platen when the platen is in inoperative position, means movable longitudinally of the platen toward the upper end thereof for feeding the sheets in succession on to the upper face of the platen, and means operated by the return of the platen to inoperative position for moving the magazine to cause the topmost sheet to contact with the feeding means. 75

3. In combination with the printing press having a type bed and a platen mounted to swing toward and from the type bed, and the means for moving the platen, of a forwarding magazine for the printed sheets at 80 the upper end of the platen when the platen is in inoperative position, means for feeding the sheets in succession from the forwarding magazine to a position to be printed on the platen, said feeding means being movable 85 longitudinally of the platen beyond the upper end thereof, and means operated by the movement of the platen into inoperative position for lifting the magazine to bring the upper sheet into contact with the feeding 90 mechanism.

4. In combination with a printing press having a type bed and a platen mounted to swing toward and from the type bed, and means for moving the platen, of a slide provided with feeding means and movable longitudinally of the platen, the platen having guideways for guiding the slide, stub shafts at the sides of the platen at the upper end thereof, arc-shaped rack bars arranged at 100 each side of the platen between the inoperative position of the platen and the type bed, a pinion secured to the outer end of each stub shaft and engaging the adjacent rack bar, a pinion secured to the inner end of each 105 stub shaft, and rack bars connected with the slide and engaging the last-named pinion.

5. The combination with the printing press having a type bed and a platen and 110 means for moving the platen, of a forwarding magazine at the upper end of the platen when the platen is in inoperative position, said magazine being adapted to contain the sheets to be printed, a support for the magazine in which the magazine is mounted to tilt, feeding means for the sheets movable longitudinally of the platen and beyond the upper end thereof, and means for tilting the magazine to bring the topmost sheet into engagement with the feeding mechanism, and a connection between the said means and the platen for operating the same to tilt the magazine when the platen moves toward the magazine. 120

6. In combination with a printing press having a type bed and a platen mounted to swing toward and from the type bed, of

means in connection with the platen for feeding the printed sheets to the platen and from the platen, a magazine for the sheets to be printed at the upper end of the platen 5 when the platen is inoperative position, and means operated by the movement of the platen to such position for moving the maga-

zine with the uppermost sheet flush with the upper face of the platen and against the feeding means.
